UNITED STATES PATENT OFFICE

2,487,765

SUPPORT

Harry O. Rugh, Chicago, Ill., assignor, by mesne assignments, to Columbia Specialties, Inc., a corporation of Illinois

Application December 7, 1945, Serial No. 633,483

3 Claims. (Cl. 242—139)

1

My invention relates to supports, and includes among its objects and advantages obtaining extreme simplification and manipulation and use in a stand or holder for rotatably supporting a reel carrying a heavy weight of material wound thereon, which material may be in the nature of insulated electrical cord.

The manufacture of electrical apparatus usually involves the cutting off and conditioning of predetermined lengths of electrical conductor from a reel on which a relatively large amount of such conductor has been wound up for storage. Such reels are quite heavy and may often weigh from 50 up to 200 or 300 pounds. And the cutting and conditioning of the individual lengths is frequently done by girls who do not have the physical strength to handle such heavy weights conveniently.

One specific advantage of the device according to the invention is that its use involves a minimum of physical effort, together with a minimum of displacement of the parts with respect to a supporting floor, combined with extreme simplicity in use. Another specific advantage is to minimize wear especially on the reel structure.

In the accompanying drawings:

Fig. 1 is a side elevation of a device according to the invention with a reel in place on it;

Fig. 2 is a plan view of the parts illustrated in Fig. 1; and

Fig. 3 is a fragmentary detail as in section on line 3—3 of Fig. 1.

In the embodiment of the invention selected for illustration, the base 10 may be a simple board. The standards 12 extend up to support the sockets 14. They may also extend along the board and be combined with a cross partition 16 to define an open box-like structure which houses the downwardly moving portion of the reel and guard against accidents due to objects or portions of an operator's clothing getting caught when the reel is rotated.

I have illustrated a conventional reel comprising duplicate end plates 18 united into a fairly rigid assembly by four tubes 20 around which the stored material 22 may be wound up to the capacity of the reel. In the drawings the reel is illustrated as somewhat more than half empty with a reach 24 extending away from the reel and constituting the portion being withdrawn from the reel.

Each end plate is provided with a central circular aperture 26. To prepare the reel for mounting on the support the pintle 28 is inserted through the openings 26 after one of the end

2

cones 30 has been removed from the pintle to permit convenient insertion. Then the cone is replaced so that the parts occupy the relative positions indicated in Fig. 2 and fastened on the pintle as by means of the set screw 32. Both cones are longitudinally slideable on the pintle 28 and provided with set screws 32 so that reels of a wide range of sizes up to and including the capacity of the support may be mounted midway between the ends of the pintle with the cones in good engagement with the end plates of the reel.

Each of the sockets 14 includes a face plate 34 fastened to the standard 12 as by wood screws 36, and a hook 38 extending outwardly and upwardly to define a semi-circular outwardly opening socket of such a diameter as to receive the pintle 28 with a little radial clearance so that the pintle turns easily in the socket. Thus the good frictional engagement between the cones and the end plates renders it certain that the pintle and cones will rotate with the reel and that sliding contact will be between the pintle and the socket where friction is small and where the parts are designed to turn under the load without excessive wear, such as would be likely to injure the end plates if the pintle did not rotate with the reel.

Upon reference to Fig. 1 it will be observed that the center of gravity of the rotating parts is just a little to the right of the heel 40 at the left end 30 of the base 10.

To bring the parts to the position of Fig. 1 with the reel ready to function as a convenient source of supply, it is only necessary to tilt the base 10 in a counter clockwise direction about 30° around the heel 40. This swings the sockets 14 to the left and downwardly until they are a little closer to the floor than the pintle is when the edges of the end plates 18 are supporting the reel on the floor. With the support in this position the reel can be rolled along the floor without lifting it until the ends of the pintle pass over the toes of the hooks 38 and strike the face plates 34. Then the operator can conveniently put one foot on the treadle 42 formed by the end of the base 10 projecting beyond the partition 16 and by stepping on it move the parts to the position of Fig. 1. It will be apparent that an operator, proceeding as above outlined can, without material effort, lift a reel from the floor into the position of Fig. 1 up to a weight amounting to about twice the weight of the operator. Furthermore, the support itself can be positioned before the reel is put in place in the exact position where the operator wants to have it after the reel is in place, and no displacement of the support from its predetermined posi-

tion is involved in tipping it up to receive the reel and back again into the position of Fig. 1.

Without further elaboration the foregoing will so fully explain my invention that others may readily adapt the same for use under various conditions of service.

I claim:

1. A reel support comprising in combination: a flat rectangular panel base; approximately square side panels about half as long as said base; said side panels being permanently assembled on said base along opposite side edges of said base, and both close to the same rear end of said base, whereby about half said base projects forward beyond said side panels to form a treadle; upwardly opening U-shaped receiving hooks at the upper rear corners of said side panels; said hooks being transversely aligned and adapted to receive a reel pintle; and a vertical cross panel connecting at least the upper portions of the front vertical edges of said side panels to define with them a box-like structure open at the top and rear; said hooks lying at an angle inclined not more than about five degrees to the vertical, with respect to the rear edge of said panel; whereby loading a reel of the size for which said support is designed may be achieved by merely lifting said treadle to tilt the entire support not more than about thirty degrees around the rear edge of said panel as a fulcrum; entering said hooks under the pintle of a reel resting on the same level as said support; and then stepping on said treadle to push it back down.

2. A reel support comprising in combination: a flat panel base; approximately square side panels about half as long as said base; said side panels being permanently assembled on said base along opposite side edges of said base and both close to the same rear end of said base; whereby almost half said base projects forward beyond said side panels to form a treadle; upwardly opening U-shaped receiving hooks at the upper rear corners of said side panels; said hooks being transversely aligned and adapted to receive a reel pintle; said hooks lying at an angle of not more than about five degrees to the vertical, with respect to the rear edge of said panel; whereby loading a reel of the size for which said support is designed may be achieved by merely lifting

said treadle to tilt the entire support not more than about thirty degrees around the rear edge of said panel as a fulcrum; entering said hooks under the pintle of a reel resting on the same level as said support; and then stepping on said treadle to push it back down.

3. A reel support comprising in combination: a flat panel base; side panels about half as long and half as high as the length of said base; said side panels being permanently assembled on said base along opposite side edges of said base and both close to the same rear end of said base; whereby almost half of said base projects forward beyond said side panels to form a treadle; upwardly opening U-shaped receiving hooks on said side panels; said hooks being transversely aligned and adapted to receive a reel pintle; and a vertical cross panel connecting at least the upper portions of the front vertical edges of said side panels to define with them a box-like structure open at the top and rear; whereby loading a reel may be achieved by merely lifting said treadle to tilt the entire support around the rear edge of said panel as a fulcrum; entering said hooks under the pintle of a reel; and then stepping on said treadle to push it back down; said receiving hooks being offset from above said fulcrum toward the treadle end of said base not more than about five degrees.

30 HARRY O. RUGH.
